UNITED STATES PATENT OFFICE.

JOHN O'DONNELL, JR., OF PHILADELPHIA, PENNSYLVANIA, ASSIGNOR OF ONE-HALF
TO LOUIS H. BROWN, OF PHILADELPHIA, PENNSYLVANIA.

DESIGN FOR A FACEPLATE FOR AUTO SIGNAL.

Application filed September 13, 1922. Serial No. 3,712. Term of patent 3½ years.

To all whom it may concern:

Be it known that I, JOHN O'DONNELL, Jr., a citizen of the United States, residing in the city and county of Philadelphia, State of Pennsylvania, have invented a new, original, and ornamental Design for Faceplate for Auto Signal, of which the following is a specification, reference being had to the accompanying drawing, forming part thereof.

Figure 1 is a face view for a faceplate for auto signal showing my new design.

Figure 2 is a side edge elevation thereof.

Figure 3 is a central vertical section on line 3—3 Figure 1.

I claim:—

The ornamental design for a faceplate for auto signal, as shown.

JOHN O'DONNELL, JR.
